UNITED STATES PATENT OFFICE

2,532,853

VANITY BACK VIEW CHAIR

William N. Parry, New Haven, Conn.

Application August 4, 1948, Serial No. 42,517

4 Claims. (Cl. 88—92)

1

This invention relates to vanity rear view chairs, adapted for use in combination with a mirror of a vanity table, a dresser, a mirror which is hung on a wall, or a mirror adapted to be seated upon a table or the like, and whereby users may obtain a clear view of the rear portion of their head, or other rear portion of their body, without the use of a hand mirror and thus have full and unrestricted use of both hands.

One object of this invention is to provide a vanity rear view chair, which when in use is adapted to have a user, seated thereon before a mirror, simultaneously observe in said mirror the front and rear portions of the body.

Another object is to provide in a chair, angularly disposable mirrors which may be adjusted vertically in respect to the seat of the chair and be readily lowered into the chair frame and form a back therefor.

A further object of this invention is to provide a vanity rear view chair, which will be relatively inexpensive to manufacture, readily manipulated, simple in construction, of pleasing appearance, compact, and very efficient and durable in use.

With the above and other objects in view, which will appear as the description proceeds, there has been illustrated in the accompanying drawings one form in which the features and principles of this invention may be practically embodied.

In the drawings:

Figure 1 is front perspective view of a chair embodying the features and principles of this invention;

Figure 2 is a side view of the same;

Figure 3 is a back view of the same;

Figure 4 is a front view of the same with certain parts thereof in an extended position;

Figure 5 is a sectional view taken on the line 5—5 of Figure 3;

Figure 6 is a sectional view taken on the line 6—6 of Figure 4, and showing certain parts in another position;

Figure 7 is a detail front view of a portion of the chair of this invention;

Figure 8 is a sectional view taken on the line 8—8 of Figure 7; and

Figure 9 is a sectional view taken on the line 9—9 of Figure 4.

Referring now to the drawings wherein like reference numerals designate like parts throughout the several views, the reference numeral 11 denotes a suitably padded seat supported from the floor by front legs 12 and back legs 13 and 14. The seat 11 rests on and is secured to front, back and side strips 15, 16 and 17 respectively, one of which extends between and is secured to the front legs 12, one between the back legs 13 and 14, one between one of the front legs 12 and the back leg 13, and one between the other of the front legs 12 and the back leg 14. The back legs 13 and 14

extend upwardly beyond the seat 11 and are joined together at their upper ends by a rail 18 which extends between them and has an end of same secured to each of the leg extensions, or risers, 19 and 21. A vertical strip 22 extends between the rail 18 and the back strip 16 and is suitably secured to each.

The above structure is substantially more or less standard and forms a chair adapted to be seated upon, by a user, in front of a common mirror while combing, arranging, or trimming, their hair, shaving, etc. By the inclusion in its structure of the features and principles of this invention such a chair is provided with means

15 whereby, while seated before the common mirror, which reflects the front portion of the body facing it, reflection of the back of the head, or rear portion of the body facing it, will also be reflected in the mirror. To obtain this advantageous result 20 a pair of panels 23 and 24, each having a mirror 25 carried thereby, are provided, and are arranged to be vertically positioned in back of the user and swung laterally to the proper angle to reflect into the common mirror and the rear portion of the 25 user's body facing the common mirror, whereby the rear portion may be observed and the user's hands will be free for any purpose desired.

The panels 23 and 24 may be hinged together at 26, although this is not always necessary, and 30 are each pivoted to a cross-strip 27 by a bolt 28 which extends through the bottom frame 29, through a transversely elongated hole 31 in the strip 27, and beyond the strip 27 to receive a nut 32. A coiled spring 33 is disposed on each bolt 35 28 between the strip 27 and the nut 32 to tightly urge the respective panel downwardly upon the strip 27. The panels 23 and 24, when in alignment laterally, are in vertical alignment with the strip 27 and the outer edge of each panel is flush 40 with the respective outer end edge of the strip 27. When in this latter position the panels 23 and 24, with the strip 27, are slideable in opposing vertical grooves 34 and 35 formed in the back leg extensions 19 and 21 respectively, and may be slid 45 downwardly until the ends of the strip 27 seat upon upwardly facing shoulders 36 and 37 provided on the extensions 19 and 21 respectively. Guide strips 38 and 39, secured one on each end of the strip 27, extend downwardly and slide in 50 the grooves 34 and 35 respectively, and in holes 41 and 42, provided in the leg extensions, or risers, 19 and 21, and back legs 13 and 14 respectively.

A ratchet toothed bar 43 is secured at its upper end to the strip 27 and extends downwardly 55 therefrom through a housing 44 secured upon the rear surface of the vertical strip 22. A spring pressed releasable catch 45 having an operating handle 46 is provided to engage the teeth in the bar 43 and releasably hold the panels 23 and 24 in any raised position above the shoulders

36 and 37. By means of the bar 43 and catch 45, the panels may be held in a position above the rail 18, if desired. A handle 47 is secured upon the adjacent side frames 48 and 49 of the panels 23 and 24 respectively, by which they may be spread apart into angular position, as shown in Figure 6, or moved into closed aligned position as shown in Figure 8. The elongated holes 31 limit the amount each of the panels may be angularly swung on the bolts 28, the bolt in each panel engaging the frame at the end of each hole. Cross bars 51, padded if desired, are attached to the upper frame 52 of each panel 23 and 24 and are of suitable size to overlie the upper ends of the leg extensions, or risers, 19 and 21, and to provide a comfortable head rest when the panels are in lowered position.

While there has been shown and described herein one form of vanity back view chair in which the features and principles of this invention may be embodied in practice, it is to be understood that they may be embodied in other specific forms without departing from the spirit and essential attributes thereof, and it is therefore desired that the present embodiment be considered in all respects as illustrative and not restrictive, reference being had to the claims rather than to the foregoing description to indicate the scope of the invention.

Having thus fully disclosed the invention, what is claimed as new and for which it is desired to obtain Letters Patent for, is:

1. In a chair, the combination of a seat, laterally spaced apart chair side extensions rising above the rear edge of said seat, and having opposing faces, a rail attached to and extending across the upper ends of said extensions, the opposing faces of said extensions having grooves formed therein lengthwise thereof and in back of said rail, a cross strip extending from one extension to the other with its ends slideable in the said grooves, a pair of panels with their lower edges resting on said cross strip and having their opposing side edges hinged together at substantially the vertical center of said chair, the cross strip having lengthwise spaced apart slots therein and a pivot pin extending through each slot of said strip and secured to each panel to pivotally secure each of the said panels to the cross strip, said panels, when disposed in laterally aligned position in respect to the chair, being adapted to slide with said cross strip in the grooves in said extensions to close the space between the side extensions and thus form a back for said chair.

2. A chair comprising a seat, laterally spaced apart side extensions rising upwardly from the rear edge of said seat, a rail attached to and extending across the upper ends of said extensions, the opposing faces of both of said extensions having a lengthwise groove therein, a cross-strip having ends slideable in the grooves in said extensions and having lengthwise extending and spaced apart elongated slots therein, a pair of laterally aligned panels seated upon said cross-strip with their inner side edges in abutting relation and their outer side edges slideable in the grooves in said extensions to close the space between the side extensions, means comprising a pivot pin secured to each panel and extending into one of the slots in said cross-strip to pivot said panels to said cross-strip to swing on a vertical axis, means at the inner edges of said panels to hinge them together, whereby said panels will swing equally and in unison about their pivotal means to said cross-strip, toothed means attached

to said cross-strip and extending downwardly therefrom, and catch means attached to said chair seat engaging said toothed means to retain said cross-strip and said panels in any vertically adjusted position in said grooves, said catch means being releasable to permit lowering of said cross-strip and panels.

3. A chair comprising a seat, a post extending upwardly from the rear of said seat substantially central between the edges thereof, a side extension extending upwardly from each side of said seat, each being spaced laterally from said central post, a lengthwise groove formed in the opposing inner edges of said side extensions to the rear of said post, a cross-strip having ends slideable in the grooves in said extensions and having lengthwise extending and spaced apart elongated slots therein a pair of laterally aligned panels seated upon said cross-strip with their inner side edges in abutting relation and their outer side edges slideable in the grooves in said extensions to close the spaces between each extension and the post, means comprising a pivot pin secured to each panel and extending into one of the slots in said cross-strip to pivot said panels to said cross-strip to swing on a vertical axis, and means at the inner edges of said panels to hinge them together, whereby said panels will swing equally and in unison about their pivotal means to said cross-strip.

4. A chair comprising a seat, a post extending upwardly from the rear of said seat substantially central between the edges thereof, a side extension extending upwardly from each side of said seat, each being spaced laterally from said central post, a lengthwise groove formed in the opposing inner edges of said side extensions to the rear of said post, a cross-strip having ends slideable in the grooves in said extensions and having lengthwise extending and spaced apart elongated slots therein a pair of laterally aligned panels seated upon said cross-strip with their inner side edges in abutting relation and their outer side edges slideable in the grooves in said extensions to close the spaces between each extension and the post, means comprising a pivot pin secured to each panel and extending into one of the slots in said cross-strip to pivot said panels to said cross-strip to swing on a vertical axis, means at the inner edges of said panels to hinge them together, whereby said panels will swing equally and in unison about their pivotal means to said cross-strip, means having teeth attached to said cross-strip and extending downwardly therefrom in back of said center post, and catch means attached to said chair seat engaging said toothed means to retain said cross-strip and said panels in any vertically adjusted position in said grooves, said catch means being releasable to permit lowering of said cross-strip and panels.
